UNITED STATES PATENT OFFICE.

FRANK C. SAMPSON, OF CHICAGO, ILLINOIS.

PHOTOGRAPHIC FRAME FOR PRINTING ON METAL.

1,280,308.

Specification of Letters Patent.

Patented Oct. 1, 1918.

Application filed October 27, 1916. Serial No. 127,983.

To all whom it may concern:

Be it known that I, FRANK C. SAMPSON, a citizen of the United States, residing at Chicago, in the county of Cook and State of Illinois, have invented certain new and useful Improvements in Photographic Frames for Printing on Metal, of which the following is a specification.

This invention relates to improvements in photographic printing frames for printing on metal and one of the objects of the invention is to provide an improved device of this character by means of which prints may be obtained from a plate, commonly designated as negatives, directly upon a sensitized metal plate for lithographing work, with the result that many of the operations heretofore necessary, such as the transferring operation in lithographing will be dispensed with.

A further object is to provide an improved device of this character, having means whereby the negative and sensitized plate may be relatively shifted one with respect to the other, so that a number of prints may be obtained from the same negative upon the sensitized plate without removing the negative from the frame.

To the attainment of these ends and the accomplishment of other new and useful objects as will appear, the invention consists on the features of novelty in substantially the construction, combination and arrangement of the several parts, hereinafter more fully described and claimed and shown in the accompanying drawings, illustrating the invention and in which:

Figure 1 is a top plan view of an improved device of this character constructed in accordance with the principles of this invention.

Fig. 2 is an end elevation as taken from the right hand end of Fig. 1.

Fig. 3 is a detail sectional view taken on the line 3—3, Fig. 1.

Fig. 4 is a sectional view taken on the line 4—4, Fig. 1.

Fig. 5 is a detail perspective view of the holder for the negative.

Fig. 6 is a top plan view of a modified form of the invention.

Fig. 7 is a sectional view on the line 7—7, Fig. 6.

Throughout the specification and claims, the term negative will be used and it is to be understood that such a term when re-

ferring to the plate from which the print is made, is to be construed to be either a negative or a positive, according to the print which is to be obtained therefrom.

Referring more particularly to the drawings, the numeral 10 designates a suitable support, having walls 11, 12, rising therefrom.

Arranged within the walls 11 and 12, is a frame designated generally by the reference numeral 13, and this frame is provided with portions 14 which project through slots 15 in the walls 11, and are of a size and width as to fit snugly within the slots, so that when the frame is moved with respect to the walls 11, the portions 14 will act as guides for accurately holding the frame in its travel.

The frame is adapted to be moved or shifted with respect to the walls 11 in any suitable manner preferably by means of gears 16, which are connected with the frame 13 at opposite ends thereof and these gears are adapted to travel along racks 17 arranged in any suitable position with respect to the walls 11, so that when the gears 16 are rotated, the frame 13 will be shifted by reason of the gears rolling over the racks.

These gears may be rotated in any suitable manner, such as by means of sprocket wheels 18, which are connected with the gears and over which sprocket wheels, a sprocket chain 19 passes. This sprocket chain also passes over suitable sprocket wheels 20 for guiding the chain and the chain may be operated by means of a suitable handle 21, connected preferably with one of the sprockets 20. Thus it will be manifest that when the handle 21 is operated to rotate the sprocket 20, the chain 19 will be correspondingly operated and the frame 13 will be moved backwardly and forwardly with respect to the support according to the direction of rotation of the handle.

The sensitized plate upon which the print is to be made is adapted to rest upon the support 10 such as at 22, and in order to cover the sensitized plate, or that portion over which the negative is not positioned, a suitable flexible element 23 is provided which is adapted to encompass the support 10, with the extremities 24 thereof secured to the opposite sides of the frame 13, as shown more clearly in Fig. 3. Suitable guide rollers 25 may be provided for the flexible member 23 to pass over and either one or both of the ex-

tremities of this flexible member are secured to the frame 13, so as to be detached therefrom by means of suitable securing devices 26, so that one or the other of the ends of the 5 flexible member may be detached to permit the sensitized plate 22 to be placed upon the support 10. Obviously the walls 12, 13 are provided with openings 26^a therein to permit the flexible member 23 to pass there- 10 through.

The walls of the frame 13 are spaced from each other for considerable distance and mounted to slide upon these walls is a negative holder 27, which is provided with ears 15 28, having internal screw threads adapted to receive screw threaded rods 29, which extend lengthwise of the walls 13 and the extremities of these rods 29 preferably project through the gears 16, 18 and beyond said 20 gears, for the reception of a gear 30, which is secured to the rod for rotation therewith. If desired both ends of the rod 29 may be provided with similar gears.

Mounted in any suitable manner, so as to 25 travel with the frame 13 and also with the gears 30 that travel with the frame, is a master gear 31, to which is connected an operating handle 32, and intermediate gears 33 are provided between the master gear 31 and 30 the gears 30 for operating the latter, so that when the gear 31 is actuated, the rods 29 will be rotated and this will cause the negative holder 27 to be shifted upon the frame 13 and in a direction transverse to the direction 35 of shifting movement of the frame. Thus it will be seen that the negative holder 27 is bodily shiftable with the frame 13 when the handle 21 is actuated and is shiftable relatively to the frame when the handle 32 40 is actuated.

A flexible member 34 also encompasses the support 10 to move in a direction transverse to the direction of movement of the flexible member 23 and suitable guide rollers 35 may 45 be provided over which the flexible member 34 passes. The extremities 36 of this flexible member may be secured as at 37 to the negative holder 27. The function of this flexible member 34 is to engage the sensitized plate between the walls of the frame work 13 so that when the negative holder 27 50 is shifted from one position to another of the sensitized plate, the remaining portion of the plate will be unexposed.

55 It will be manifest that by shifting the frame 13 and the negative holder 27, the negative may be moved to any desired position with respect to the sensitized plate and as many prints may be obtained from the 60 negative on the plate as is desired, without removing the negative. In order to insure the negative 38 standing in close proximity to the plate 22, any suitable means may be provided. A simple and efficient means 65 comprises adjusting screws 39 which pass

through the wall of the negative holder, which latter rests upon the negative 38 and the negative in turn rests upon supporting shoulders 41 on the negative holder. Thus it will be seen that by adjusting the screws 70 39, the negative will be forced tightly against the sensitized plate.

Lifting devices 42 may be connected with the glass holder 40 to assist in removing the same from the negative holder. 75

In the form of the invention shown in Figs. 6 and 7, the negative holder 43 remains stationary and the support 44 upon which the sensitized plate 22 rests is adapted to be adjusted first in one direction and then in a direction transverse thereto so that the sensitized plate will be moved with respect to the negative. This may be accomplished in any suitable manner, such for instance by mounting the support 44 so that it 80 will travel upon a base 45 in one direction when an operating screw threaded shaft 46, which engages threaded ears 47 is actuated by means of an operating handle 48. The shaft 46 is mounted in suitable bearings 49 85 having portions 50 which travel in suitable guides 51 upon the support 45, so that when another threaded shaft 52 which extends in a direction transverse to the shaft 46 is actuated by a suitable actuating handle 53, the support 44 will be moved in a direction transverse to the direction of movement given to the support by the shaft 46.

It will thus be manifest that with this improved construction, a simple, durable and efficient structure is produced and by the use of which a number of prints may be readily obtained from a single negative and the negative and sensitized plate will be relatively adjusted one with respect to the other 90 95 100 to accomplish this end and at the same time the portion of the sensitized plate which is not in a position to be exposed through the negative will be covered and protected against the light rays by the flexible elements 23, 24. 105

Obviously these flexible elements may be of any desired or suitable construction.

While the preferred forms of the invention have been herein shown and described, 115 it is to be understood that many changes may be made in the details of construction and in the combination and arrangement of the several parts without departing from the spirit of this invention.

What is claimed as new is:

1. A device of the character described embodying means for holding a sensitized metallic sheet, a negative holder for holding the negative in close proximity to the sheet, 125 said sensitized sheet being of an area considerably greater than the area of the negative, means for relatively shifting the said sheet and the negative one with relation to the other, and automatically adjustable 130 135 140

means for covering all of the sensitized sheet except the portion over which the negative stands.

2. A device of the character described embodying means for holding a sensitized metallic sheet, a negative holder for holding the negative in close proximity to the sheet, said sensitized sheet being of an area considerably greater than the area of the negative, means for relatively shifting the said sheet and the negative one with relation to the other, means for causing the negative and sheet to be pressed close together, and automatically adjustable means 10 for covering all of the sensitized sheet except the portion over which the negative stands.

3. A device of the character described, embodying means for holding a sensitized metallic sheet, a negative holder for holding the negative in close proximity to the sheet, said sensitized sheet being of an area considerably greater than the area of the negative, means for relatively shifting the said sheet and the negative one with relation to the other, and means for covering all of the sensitized plate except the portion over which the negative stands.

4. A device of the character described embodying means for holding a sensitized metallic sheet, a negative holder for holding the negative in close proximity to the sheet, said sensitized sheet being of an area considerably greater than the area of the negative, means for relatively shifting the said sheet and the negative one with relation to the other, and shiftable means for covering all of the sensitized plate except the portion over which the negative stands, the last said 40 means being responsive in its shifting movement to the relative movement of the negative and the said sensitized sheet.

5. A machine of the character described, embodying a support for receiving a sensitized plate, guides projecting above the support, a frame movable upon the guides, a flexible element encompassing the support and having its ends connected with the frame, whereby the movement of the frame 50 in its guides will correspondingly move the said element, a negative holder movable in the frame and across the plate in a direction transverse to the direction of movement of the frame thereacross, and a flexible element encompassing the said support and having its ends connected with the negative holder, whereby the shifting of the holder will correspondingly shift the last said flexible member, the latter extending across the 55 support between the ends of the first recited flexible element, said flexible members being adapted to extend over and cover the said plate.

6. A machine of the character described, embodying a support for receiving a sensi-

tized plate, guides projecting above the support, a frame movable upon the guides, a flexible element encompassing the support and having its ends connected with the frame, whereby the movement of the frame 70 in its guides will correspondingly move the said element, a negative holder movable in the frame and across the plate in a direction transverse to the direction of movement of the frame thereacross, a flexible element encompassing the said support and having its ends connected with the negative holder, whereby the shifting of the holder will correspondingly shift the last said flexible member, the latter extending across the support between the ends of the first recited flexible element, said flexible members being adapted to extend over and cover the said plate, and means for shifting the said frame and the said negative holder independently 75 with respect to each other.

7. A machine of the character described, embodying a support for receiving a sensitized plate, guides projecting above the support, a frame movable upon the guides, a flexible element encompassing the support and having its ends connected with the frame, whereby the movement of the frame 90 in its guides will correspondingly move the said element, a negative holder movable in the frame and across the plate in a direction transverse to the direction of movement of the frame thereacross, a flexible element encompassing the said support and having its ends connected with the negative holder, 95 whereby the shifting of the holder will correspondingly shift the last said flexible member, the latter extending across the support between the ends of the first recited flexible element, said flexible members being adapted to extend over and cover the said plate, and means embodying a gear and rack for shifting the said frame with relation to the support.

8. A machine of the character described 110 embodying a support for holding a sensitized plate, slotted uprights projecting above the support, a frame having portions projecting into the slots to move therein when the frame is shifted, a flexible element encompassing the support and having its ends connected with the frame, a gear connected with the frame, a rack upon which the gear is adapted to move to shift the frame, means for rotating the gear, a negative holder movable upon the frame across the support and in a direction transverse to the direction of movement of the frame thereacross, and a flexible element encompassing the support and projecting between the ends of the first 115 recited flexible member, the ends of the second said flexible member being connected with the said negative holder.

9. A machine of the character described, embodying a support for holding a sensi- 120

- 4
- tized plate, slotted uprights projecting above the support, a frame having portions projecting into the slots to move therein when the frame is shifted, a flexible element encompassing the support and having its ends connected with the frame, a rack upon which the gear is adapted to move to shift the frame, means for rotating the gear, a negative holder movable upon the frame across the support and in a direction transverse to the direction of movement of the frame thereacross, a flexible element encompassing the support and projecting between the ends of the first recited flexible member, the ends of the second said flexible member being connected with the said negative holder, and means embodying a feed screw and operating mechanism therefor for shifting the said holder in the frame.
- 10 10. A machine of the character described embodying a support for holding a sensitized plate, a plurality of shiftable frames mounted upon the support, said frames be-

ing bodily movable together back and forth over the support in the same direction, one of said frames being shiftable across the support independently of the other frame and in a direction transverse to the direction of movement of the other frame across the support, means for imparting such movements to the frames, flexible elements individual to the frames and encompassing the support, the ends of the flexible elements being secured to the respective frames and adapted to cover the plate, and means for holding a negative in one of the frames in close proximity to the said plate.

25 30 35 In testimony whereof I have signed my name to this specification, in the presence of two subscribing witnesses, on this 21st day 40 of October, A. D. 1916.

FRANK C. SAMPSON.
